US00D992359S

(12) **United States Design Patent** (10) **Patent No.:** **US D992,359 S**
(45) **Date of Patent:** **** Jul. 18, 2023**

(54) **INSULATING DEVICE**

- (71) Applicant: **YETI Coolers, LLC**, Austin, TX (US)
(72) Inventors: **Mark Carlson Rane**, Austin, TX (US);
Dustin Bullock, Austin, TX (US)
(73) Assignee: **YETI Coolers, LLC**, Austin, TX (US)
(**) Term: **15 Years**
(21) Appl. No.: **29/770,660**
(22) Filed: **Feb. 15, 2021**

Related U.S. Application Data

- (63) Continuation of application No. 29/655,306, filed on Jul. 2, 2018, now Pat. No. Des. 910,382, which is a continuation of application No. 29/604,256, filed on May 16, 2017, now Pat. No. Des. 821,824.

CLAIM

The ornamental design for an insulating device, as shown and described.

DESCRIPTION

FIG. 1 is a top, front, left perspective view of an insulating device showing our new design in an open configuration; FIG. 2 is a front view thereof; FIG. 3 is a rear view thereof; FIG. 4 is a right side view thereof; FIG. 5 is a left side view thereof; FIG. 6 is a top view thereof; FIG. 7 is a bottom view thereof; FIG. 8 is a top, front, left perspective view of an insulating device showing our new design in a closed configuration; FIG. 9 is a front view thereof; FIG. 10 is a rear view thereof; FIG. 11 is a right side view thereof; FIG. 12 is a left side view thereof; FIG. 13 is a top view thereof; and, FIG. 14 is a bottom view thereof.

The broken lines showing the remainder of the insulating device represent unclaimed subject matter and form no part of the claimed design.

1 Claim, 14 Drawing Sheets
